UNITED STATES PATENT OFFICE.

E. WALTER MORRIS, OF BLOOMFIELD, NEW JERSEY.

SASH-HOLDER.

SPECIFICATION forming part of Letters Patent No. 337,695, dated March 9, 1886.

Application filed July 6, 1885. Serial No. 170,753. (No model.)

To all whom it may concern:

Be it known that I, E. WALTER MORRIS, of Bloomfield, in the county of Essex and State of New Jersey, have invented certain new and 5 useful Improvements in Sash-Holders; and I do hereby declare that the following is a full, clear, and exact description of the invention, which will enable others skilled in the art to which it appertains to make and use the same, 10 reference being had to the accompanying drawings, which form a part of this specification, and in which—

Figure 1 is a side elevation of sash-holder in use. Fig. 2 is a plan of same. Fig. 3 is a side 15 elevation of sash-holder used for locking the window.

The object of my invention is to provide by 20 an automatic sash-holder means for holding window-sashes in any desired position, preventing them from rattling, and when the windows are closed to use the same for locking them. It will be seen that in railroad or other 25 cars the windows fitted with this attachment can be opened as may be desired by the occupants, and they will be prevented from being closed by weight of sash or the vibration of the car without the aid of catches or other similar devices.

My invention consists of a box-frame fastened to the window-sash by screws. The 30 frame has a stationary hand-piece for adjusting the loose lever which operates the wedge. It will be seen that when the wedge is in a vertical position and the sash being 35 raised immediately it is let go the wedge tightens itself by binding against the frame and the incline plane of the box side, and hence the window is held in any desired position. The hole in the lever on which the wedge is 40 hung is somewhat elongated for the purpose of allowing the heavy or lower part of the

wedge to overbalance the top or lighter part, causing it to angle into the recess on the side of the frame to receive it, so that when the window is closed it virtually forms a lock, 45 thus preventing the window from being raised. The wedge is slotted, so as to receive some binding material—such as rubber, vulcanite composition, or wood. A spring may be used to keep the wedge in a vertical position when 50 the locking arrangement is not required.

In Figs. 1, 2, and 3, C is the box-frame for screwing to sash, which has a stationary hand-piece attached.

A is the lever with handle for adjusting the 55 wedge, having the elongated hole E, into which the fulcrum-pin D extends.

P is the pin on which the wedge is hung and held in position.

B is the wedge itself, and F is the slotted 60 recess for receiving the binding material.

Y is the sash on which the box C is screwed, and X is the side frame.

G is the box which is fitted to the frame X for receiving the wedge when inclined to lock 65 the window.

Having thus described my invention, what I claim, and desire to secure by Letters Patent, is—

In a sash-holder, the combination of the box 70 C, provided with the fulcrum-pin D and an inclined face, with the wedge-shaped block B and the lever A, to which the wedge is pivoted, the bearing E in said lever being elongated, for the purposes specified and set forth. 75

In testimony that I claim the foregoing as my own I have hereunto affixed my signature in presence of two witnesses.

E. W. MORRIS.
